DESIGN FOR A GRATE

Albert Hoiland, Lansing, Mich.

Application February 7, 1945, Serial No. 117,793

Term of patent 14 years

(Cl. D81—18)

To all whom it may concern:

Be it known that I, Albert Hoiland, a citizen of the United States, residing at Lansing, county of Ingham, and State of Michigan, have invented a new, original, and ornamental Design for a Grate, of which the following is a specification, reference being had to the accompanying drawing, forming part thereof:

I claim:

The ornamental design for a grate, as shown.

ALBERT HOILAND.
